W. A. DOBLE.

SPEED GOVERNOR.

APPLICATION FILED JULY 11, 1917.

1,319,463.

Patented Oct. 21, 1919.

UNITED STATES PATENT OFFICE.

WILLIAM A. DOBLE, OF SAN FRANCISCO, CALIFORNIA.

SPEED-GOVERNOR.

1,319,463.

Specification of Letters Patent. Patented Oct. 21, 1919.

Original application filed June 2, 1913, Serial No. 771,308. Patent No. 1,234,882, dated July 31, 1917. Divided and this application filed July 11, 1917. Serial No. 179,963.

To all whom it may concern:

Be it known that I, WILLIAM A. DOBLE, a citizen of the United States, and a resident of San Francisco, county of San Francisco, 5 and State of California, have invented certain new and useful Improvements in Speed-Governors, of which the following is a specification.

This invention relates to improvements in speed controlling apparatus for motors and more particularly to that class of speed controlling apparatus which is adapted for use in connection with water wheels used for driving electric generators.

The invention belongs to that type of speed controlling apparatus in which the speed responsive or governing element controls the gate, or other device for regulating the supply of motive energy, by means of a relay mechanism.

One of the objects of the invention is to provide a mechanism of this class in which the gate or analogous device is moved by fluid pressure means and the controlling or 25 pilot valve for the fluid pressure means is moved in definite relation to the gate so that for every position of the gate there is a corresponding position for the pilot valve.

Another object is to provide a speed controlling apparatus having an "anti-racing" device which is so constructed that the movement of the gate, due to a given change in the speed of the motor, varies according to the load on the motor or the gate opening.

In speed controlling apparatus as heretofore constructed anti-racing devices have been provided which have been of the "uniformly-acting" type in which the change in the position of the gate depends entirely upon the change in speed regardless of the load on the motor. With such devices the motor will "race" because the speed is affected more by the same gate change when the motor is working under small load than under full load. The quantity of water flowing through the gate of a water wheel controlled by an apparatus of this type has been heretofore made to change proportionally to the speed of the water wheel at all loads, and to suit full load conditions. If the water wheel runs under small load, then the gate changes caused by the governor by speed variations will be too large and a racing of the water wheel will occur. In my 55 invention the apparatus is so constructed

that the gate change is smaller for a small load than for a full load.

Other objects and the various features of novelty will be apparent from the following description taken in connection with the accompanying drawings, in which:

Figure 1 is a longitudinal section through a water wheel nozzle and the apparatus for controlling the flow through the nozzle.

Fig. 2 is a vertical section of the pilot 65 valve shown in Fig. 1 and taken on a plane at right angles to the plane of Fig. 1.

Fig. 3 is a plan view of certain details shown in Fig. 1.

Fig. 4 is a section on the line 4—4 of 70 Fig. 1.

Fig. 5 is a side view of a detail.

Referring to the drawings, it will be seen that this application which is a division of my application #771,308, filed June 2, 1913, 75 and patented July 31, 1917, No. 1,234,882, shows a speed controlling mechanism in connection with a water wheel, the casing of the wheel being indicated at 130 and the buckets at 31. Water is supplied to the wheel 80 through the nozzle 132, which is secured to the nozzle body 133 and controlled by the needle valve 134. The stem 135 of the needle valve extends through the wall of the nozzle body, the latter being provided with a 85 suitable stuffing box 136 to prevent leakage. A servo-motor cylinder 137 may be mounted on any suitable support, or may be connected with the nozzle body by means of an extension 138 as shown in Fig. 1. Within 90 the cylinder 137 is a piston 139 which is secured to the stem 135 of the needle valve. The stem 135 extends through the rear head of the cylinder 137 and has its outer end portion 140 screw-threaded. A hand wheel 95 141 is arranged on the threaded portion 140 of the stem 135 and is prevented from turning off the end of the stem by means of a nut 142. A sleeve 143 is secured to the rear head of the cylinder 137 and acts as a guide for 100 the outer end of the stem 135. This sleeve is provided with a cupped outer end 144 which is adapted to coöperate with the inner end of the hub of the wheel 141 to form a dash pot for the purpose of cushioning the closing 105 movement of the needle valve.

Secured to the side of the cylinder 137 is a valve casing 145, in which is arranged a piston valve 146 and a pilot valve 147. The valve casing 145 may be provided with 110

annular passages 148, 149, 150 and 151 surrounding the valve 146 and the latter may be provided with suitable ports registering with these passages. As will be seen from Fig. 1 the passage 149 has communication with one end of the cylinder 137 by means of a port 152 and the passage 151 has communication with the other end of the cylinder by means of a port 153. From Fig. 2 it will be seen that the passage 148 communicates with the exhaust pipe 154 by means of a port 155, this port also being in communication with the space 156 in the valve casing below the valve 146. The passage 150 has communication with an inlet pipe 157 which is connected with a suitable source of liquid under pressure for operating the servo-motor.

Secured to the upper part of the valve casing 145 are upwardly projecting arms 158 which carry a table 159, to which is secured the bracket 160 of the governor. A sleeve 161 is secured to the bracket 160 by means of a suitable screw 162 and has rotatably mounted thereon a bevel gear 163 and the sleeves 164 and 165. The sleeve 161 is provided with a shoulder 166 which engages the upper end of the sleeve 164 and holds the latter against longitudinal movement along the sleeve. Springs 167 have their ends secured to the sleeves 164 and 165 and carry the centrifugal weights 168.

The sleeve 165 has arranged therein the head 169 of a rod 170 which has its lower end secured to the pilot valve 147. The connection between the head 169 of the rod 170 and the sleeve 165 permits the sleeve to rotate without rotating the rod, but moves the rod with the sleeve as the latter moves up and down on the sleeve 161 due to the action of the governor weights 168.

A link 171 is pivotally secured to the lower side of the table 159 and to one end of a pair of horizontally arranged levers 172. The levers 172 are pivotally connected with the piston valve 146 and are provided with slots 173 in which a pivot pin 174 is adjustably arranged. A collar 175 is secured to the stem 135 of the needle valve and pivotally connected with one end of a link 176, the other end of this link engaging the pivot pin 174.

A bevel gear 177 meshes with the gear 163 and is arranged on a suitable shaft which may be driven by means of a pulley 178, in the usual manner, this pulley being driven by a belt 179 from the shaft of the water wheel. The hub of the hand wheel 141 may be provided with a circumferential groove 180 which is adapted to register with a suitable slot 181 in the sleeve 143 when the hand wheel is at its innermost position. A plate 182 having an opening 183 in one side thereof adapted to fit the groove 180 of the hand wheel 141 may be

inserted in the slot 181 and thereby lock the hand wheel against movement longitudinally of the stem 135 of the needle valve. The plate 182 is shown in dotted lines in this position in Fig. 4. For the purpose of draining the valve casing whenever desired a valve 184 may be provided.

In order to force the piston valve 146 downwardly and hold the connections between the valve and the stem 135 of the needle valve under tension and thus avoid lost motion a spring 185 may be arranged to bear against the under side of the table 159 and on a suitable place 186 which rests on the top of the piston valve.

The operation of this mechanism is as follows:

Assuming that the needle valve 134 is closed and that the parts are therefore at rest the valve 134 will be held in closed position by the pressure of the water thereon. When it is desired to start the wheel the hand wheel 141 can be turned to draw the valve 134 away from its seat and thus permit water to flow through the nozzle 132. This will start the wheel and as the latter increases in speed the centrifugal weights 168 will move outward and draw the sleeve 165 and the rod 170 downwardly. As the valve 134 is opened the valve 146 will be raised by means of the link 176 and the levers 172 and, since the pilot valve 174 is secured to the rod 170, the pilot valve will descend as the speed of the water wheel increases. If the opening of the needle valve 134 is just sufficient to maintain the normal speed of the water wheel the parts will remain substantially in the position shown in Fig. 1. If the speed of the wheel increases for any reason the centrifugal weights 168 will move outwardly and lower the pilot valve and uncover the ports of the piston valve 146 so that water will flow from the passage 150 through the passage 151 and thence into the cylinder 137 where the pressure acting on the piston 139 will move the needle valve 134 toward the closed position and thereby diminish the flow of water through the nozzle. This will effect a reduction in the speed of the wheel to the normal. As the needle valve moves toward the closed position the link 176 and levers 172 will draw the valve 146 downwardly until the pilot valve again covers the ports and prevents water from flowing from the passage 150 into the passage 151. It will be observed that whenever water is allowed to flow from the inlet passage 150 to one end of the cylinder 137, owing to a movement of the pilot valve, the water in the other end of the cylinder will be permitted to discharge through suitable ports in the valve 146 and into the exhaust port 155.

When the speed of the water wheel is reduced for any reason the centrifugal weights 130

168 will be moved inwardly and raise the pilot valve so as to permit water to flow from the inlet passage 150 through the passage 149 and the port 152 into the cylinder 137 and thus further open the needle valve 134 and permit additional water to be supplied to the wheel. This will restore the speed of the wheel to normal. By the action of the link 176 and the levers 172 the piston valve 146 is made to follow the movements of the needle valve 134 and thereby cut off the supply of water to the cylinder 137 as soon as the valve 134 is moved sufficiently to supply the additional water necessary to restore the speed of the wheel.

In Fig. 1, I have indicated five positions, *a*, *b*, *c*, *d* and *e* of the pivot which connects the link 176 with the collar 175 corresponding with five equally spaced positions *a'*, *b'*, *c'*, *d'* and *e'* of the pivot 174 which connects the link 176 with the levers 172. The positions *a* and *a'* indicate a position of the needle valve 134 in which it is but slightly open and the positions *e*, *e'* indicate the fully open position of this valve. The pilot valve 147 will be moved up or down in the piston valve 146 equal distances for equal changes of speed, and the piston valve 146 will therefore have to be moved the same distance as the pilot valve in order to restore the parts after the needle valve has been shifted.

In order to properly control the speed of the motor at various loads it is essential to make larger variations in the discharge through the nozzle 132 for given changes in speed at full load than at partial loads. From Fig. 1 it will be seen that the mechanism which I have devised accomplishes this purpose. When the needle valve 134 is fully opened the pivot 174 will stand at the position *e'* and assuming that a given change in speed causes this pivot to be shifted to the position *d'* it will be seen that the corresponding movement of the needle valve is represented by the distance between the positions *d* and *e* of the pivot connecting the link 176 with the collar 175. When the needle valve 134 stands slightly open with the pivot 174 at the position *b* the corresponding position of the pivot 174 will be at *b'* and the same change in speed as caused the pivot 174 to be shifted from the position *e'* to *d'* will cause this pivot to be shifted from the position *b'* to *a'*, the corresponding movement of the valve 134 being indicated by the distance between the positions *b* and *a*. This distance between the positions *b* and *a* is much smaller than that between the positions *e* and *d* and therefore the variations in the quantity of water discharged through

the nozzle will be much less for a small load than for a full load.

Having described the invention what is claimed and desired to be secured by Letters Patent is:

1. In an apparatus of the class described, the combination of a controlling element, fluid pressure means for operating said controlling element, and valve means for controlling said fluid pressure means comprising a valve connected with said controlling element and adapted to be moved by the uniform movements of the latter, different distances dependent upon the position of the controlling element.

2. In an apparatus of the class described, the combination of a controlling element, fluid pressure means for operating said controlling element, and valve means for controlling said fluid pressure means comprising a valve, and means connecting said valve with said controlling element whereby the valve is moved a greater distance by a given movement of the controlling element when the latter is at one part of its stroke than it is by a corresponding movement of the controlling element in another part of its stroke.

3. In an apparatus of the class described, the combination of a controlling element, means for operating said controlling element, and means for controlling said operating means comprising a speed responsive device, a member actuated by said speed responsive device, a second member co-operating with said first member, and means connecting said second member and said controlling element whereby the second member is moved a greater distance by a given movement of the controlling element when the latter is at one part of its stroke than it is by the corresponding movement of the element in another part of its stroke.

4. In an apparatus of the class described, the combination of a controlling element, means for operating said controlling element, and means for controlling said operating means comprising a speed responsive device, a member actuated by said speed responsive device, a second member co-operating with said first member, and adjustable means connecting said second member and said controlling element, whereby the second member is moved a greater distance by a given movement of the controlling element when the latter is at one part of its stroke than it is by a corresponding movement of the element in another part of its stroke.

In testimony whereof I affix my signature.

WILLIAM A. DOBLE.
